UNITED STATES PATENT OFFICE.

WILLIAM E. LAWRENCE, OF NEW YORK, N. Y.

WOOD-BORING MACHINE.

SPECIFICATION forming part of Letters Patent No. 256,337, dated April 11, 1882.

Application filed January 27, 1882. (No model.)

To all whom it may concern:

Be it known that I, WILLIAM E. LAWRENCE, a citizen of the United States, and a resident of the city, county, and State of New York, 5 have invented certain Improvements in Wood-Boring Machines, of which the following is a specification.

My invention relates to that class of wood-boring machines in which an auger is carried 10 by a traveling frame, and the latter is raised by means of a rack gearing with a pinion on the driving-shaft; and my invention has for its object to simplify the construction and increase the efficiency of the machine.

15 In the drawings, Figure 1 is a sectional elevation, and Fig. 2 a front elevation, of a boring machine with my improvements.

The base A, side pieces, B B', sliding frame C, boring-bar D, and driving-shaft E, both turning in bearings of said frame, and the bevel-gears $a a'$ on the bar and shaft, are all similar to those in ordinary machines of this kind, and need not be here further described.

Upon the shaft is fixed a toothed pinion, b, 25 and on the inside of the side piece B, opposite said pinion, is arranged a rack-bar, F, having at the back edge three lugs, $d d' f$, the center lug, f , being perforated to receive an eccentric pin, e , upon a cylinder, G, turning in a hole 30 in the side piece, and provided at the outer end with a crank-handle, g , whereby it may be turned so as to carry the bar to or from the pinion b .

It will be seen that the motion imparted to 35 the bar is in a curve, for which reason I make the guide-slots i in the lugs $d d'$ also curved, said slots receiving stationary pins n , project-

ing from the side piece. By this construction the bar is locked in whichever position it is adjusted. Thus when turned to the position 40 shown in Fig. 1 its teeth engage with those of the pinion b , and the boring-bar frame is raised by turning the driving-shaft, and the pressure upon the bar in any direction cannot force it back and away from contact with the pinion, 45 owing to the peculiar form of the lock-slots.

By a single movement of the hand the handle g may be turned to the position shown in dotted lines, when the bar will be carried away from the pinion, and will be locked 50 securely in this position until the handle is again swung forward.

It will be seen that when the bar is carried back it is so far removed at all points from the pinion b that it cannot engage therewith until 55 the rock-cylinder is again turned.

I claim—

The combination, in a boring-machine, of the sliding frame, carrying the geared boring-bar, and driving-shaft provided with a fixed 60 pinion, b , and a rack-bar, F, having curved slots i , receiving pins n , projecting from the side piece, and a rocking cylinder, G, provided with a handle, and with a pin, e , fitting a socket in the rack-bar, substantially as set 65 forth.

In testimony whereof I have signed my name to this specification in the presence of two subscribing witnesses.

WILLIAM E. LAWRENCE.
